UNITED STATES PATENT OFFICE.

FRANCIS A. HOWARTH AND WILLIAM W. ARMOUR, OF WORCESTER, MASSACHUSETTS;
SAID ARMOUR ASSIGNOR TO SAID HOWARTH.

STRUT FOR AUTOMATIC SPRINKLERS.

1,263,417.

Specification of Letters Patent. Patented Apr. 23, 1918.

Application filed November 29, 1915. Serial No. 64,163.

To all whom it may concern:

Be it known that we, FRANCIS A. HOWARTH and WILLIAM W. ARMOUR, both citizens of the United States, residing at Worcester, in 5 the county of Worcester and Commonwealth of Massachusetts, have invented a new and useful Improvement in a Strut for Automatic Sprinklers, of which the following is a specification accompanied by drawings, 10 forming a part of the same.

The object of our present invention is to provide a collapsible strut for closing the nozzle in a sprinkler head in which the construction is simplified, and its operation 15 rendered more accurate and certain. We accomplish this object, among others, by the construction and arrangement of parts as hereinafter described, the novel features being pointed out in the appended claims.

20 Referring to the accompanying drawings, Figure 1 represents a front view of a sprinkler head embodying our invention.

Fig. 2 is a side view of our improved strut removed from the sprinkler head.

25 Fig. 3 is a longitudinal sectional view of the same.

Figs. 4 and 5 are perspective views of the two component parts of our improved strut.

Fig. 6 is a detached view of the locking 30 piece.

Similar reference characters refer to similar parts in the different figures.

Referring to Fig. 1 of the drawings, 1 denotes a screwthreaded nozzle adapted to 35 be applied to a water supply pipe, the opening through the nozzle being closed by a cap 2 which is held in place by a pressure applied by means of a screw 3 through the interposition of a strut 4. The screw 3 is held 40 in an internally threaded hub 5 supported upon the nozzle by arms 6, 6. Supported by the framework of the sprinkler head is a water distributer 7 having a notched or serrated periphery against which a stream of 45 water when released from the nozzle 1 strikes and is distributed in a spray over a comparatively large area surrounding the sprinkler head.

The strut 4, to which our present invention relates, comprises two parts 8 and 9, 50 each formed of sheet metal and of uniform thickness throughout its length. Each of the parts 8 and 9 is therefore adapted to be formed from sheet metal at a single operation in a drop press by means of suitable

punches and dies, thereby materially reducing the cost of manufacture. The part 8 of the strut is offset at 10 to form a curved shoulder 11 against which the curved upper end of the part 9 contacts. The upper end 60 of the part 8 is provided with a laterally extended flange 12. The part 9 contacts throughout its entire length with the part 8 and its lower end is provided with a laterally extended flange 13. The flange 12 is 65 recessed at 14 to receive the tip 15 of the screw 3 and the flange 13 is recessed at 16 to receive the tip 17 of the cap 2, said recesses 14 and 16 being in alinement and slightly offset to one side of the shoulder 11. 70 An opening 18 is formed in the part 8 having its lower wall beveled, as shown at 19, Figs. 3 and 4, and the part 9 is provided with an opening 20 in alinement with the opening 18, and having its lower wall bevelled, as shown at 21, Figs. 3 and 5. In stamping the pieces 8 and 9 to form the openings 18 and 20, a portion of the metal of each is turned outwardly to form flanges 22 on the part 8 and 23 on the part 9. The 80 two pieces 8 and 9 are placed in contact in the position shown in Figs. 2 and 3, and a locking piece 24 is inserted through the openings 18 and 20. The locking piece 24 is provided with a V-shaped notch 25 on its 85 lower edge fitting the beveled surfaces 19 and 21. The space between the upper edge 26 of the locking piece 24 and the flanges 22 and 23 are filled with a fusible metal bar 27, said bar being fusible at a predetermined 90 degree of heat usually about 160°. The pressure exerted upon the flange 12 is received upon the cap 2 when the parts 8 and 9 have been united by the locking piece 24 and the fusible bar 27, but a strain is imparted to the 95 piece 8 to move its lower end in the direction of the arrow 28, Fig. 2. As soon as the fusible bar 27 is melted, the locking piece 24 is allowed to rise, permitting the movement of the part 8 in the direction of the arrow 100 28, thereby collapsing the strut and releasing the cap 2.

We claim:

1. A strut for an automatic sprinkler, comprising separate members normally held 105 in contact, but separable by a rocking movement of one member about the end of the other member as a fulcrum and each member having a beveled surface, a locking piece passing through both of said members and 110

engaging the beveled surface on each of said members, and fusible means for holding said locking piece in position.

2. A strut for an automatic sprinkler, comprising two separate members normally held in contact but separable by a longitudinal strain applied to the strut, said members having alined openings, each of said openings having oppositely inclined walls on corresponding sides of the opening forming a salient angle, a locking piece held in said openings, and having a notched side fitting said oppositely inclined sides of said openings, and means fusible at a predetermined 15 temperature for holding said locking piece in position.

3. A strut for an automatic sprinkler comprising two members normally held in contact but separable by a longitudinal strain applied to the ends of the strut, whereby a 20 swinging movement is imparted to one member about the end of the other member, said members having alined openings and oppositely extended flanges above said openings, 25 a locking piece held in said openings, and

projecting beyond said members, and a fusible bar held between said locking piece and said flanges.

4. A strut for an automatic sprinkler, comprising two members normally held in contact, but separable by a longitudinal strain applied to the axis of the strut, said members being formed of sheet metal and having at opposite ends of the strut flanges extending in the same direction, said members having alined openings, with the lower wall of said openings beveled in opposite directions to form a salient angle, a locking piece having a V-shaped notch engaging said angular wall of the openings, but of 35 less width than the width of said openings, and a fusible material filling the remainder of said openings.

Dated this 23rd day of November, 1915.

FRANCIS A. HOWARTH.
WILLIAM W. ARMOUR.
